UNITED STATES PATENT OFFICE

2,445,236

APPARATUS EMPLOYING CAVITY
RESONATORSLeon S. Nergaard, Princeton, N. J., assignor to
Radio Corporation of America, a corporation of
Delaware

Application July 28, 1944, Serial No. 547,010

3 Claims. (Cl. 315—39)

1

My invention relates to apparatus for use at ultra-high frequencies, and more particularly to electron discharge devices and associated circuits of the cavity resonator type.

In my co-pending application, Serial No. 531,312, filed April 17, 1944, and assigned to the same assignee as the present application, I describe a novel tube of the triode type utilizing cavity resonator circuits. In some applications it may be desirable to operate the input cavity resonator in the fundamental mode. This can be accomplished if the resonator can be made small enough. However with the construction shown in the above identified application it is difficult to accomplish this mode of operation.

It is, therefore, an object of my present invention to provide an electron discharge device and associated circuit of the cavity resonator type in which the cathode-grid resonator or input resonator may be operated in the fundamental mode.

More specifically it is an object of my invention to so design the cathode-grid cavity resonator which will permit tuning and fundamental mode operation without changing the design of the tube described in the above-mentioned application.

The novel features which I believe to be characteristic of my invention are set forth with particularity in the appended claims, but the invention itself will best be understood by reference to the following description taken in connection with the accompanying drawing in which Figure 1 is a longitudinal section of an electron discharge device and associated circuit made according to my invention and now Patent No. 2,341,273, granted November 18, 1947, and Figure 2 is a longitudinal section of a modification of the electron discharge device and circuit shown in Figure 1.

In Figure 1 I describe an electron discharge device comprising an indirectly heated cup-shaped cathode 20 nested within the grid 19 and anode 12 provided with the cooling fins 13. The anode is provided with the collar 14 sealed to insulating collar member 15 which in turn is sealed to a second collar 16 by which the grid 19 is supported. This collar is provided with a transverse flange 27. The cathode electrode is insulatingly supported from the base of the tube and sealed through the collar 17. The cathode leads 18 extend through the collar member 17.

The output cavity resonator is of the half-wave type and comprises inner conductor 21 secured to the anode and an outer conductor 22 having an aperture 24 surrounded by the outer conductor 24'

2

of a coaxial line, and through which extends the inner conductor 23 of the coaxial line. The inner conductor 23 is capacitively coupled to the line 21. Voltage is applied to the anode at a voltage node by means of conductor 26 extending through aperture 25. The flange 27 is clamped to the plate 22' closing the lower end of the outer coaxial conductor 22 by means of radially slidable segmentally shaped clamps 28 which may be fixed in position by means of the screw members 29.

In order to operate in a fundamental mode the input cavity resonator must be made as small as possible. According to my invention I utilize the cathode pins 18 as the inner conductor of a transmission line. The plate 22' carries conducting collar 30 coaxial with and extending parallel to the cathode pins 18. Mounted between the pins 18 and the collar 30 is a sliding short circuit capacity device comprising an outer ring 31 having spring fingers 31' and an inner ring 32 having spring fingers 32', these rings being insulatively separated from each other by means of the insulating collar 34 preferably of mica. This shorting condenser may be positioned so that the pins 18 and collar 30 act as the inner and outer conductors of a coaxial line cavity resonator between the cathode and grid. The compact arrangement described will thus function at a very high frequency in a fundamental mode. Feedback may be provided by the cathode-anode capacity within the tube.

In the modification shown in Figure 2 like members designate like parts as in Figure 1. In this arrangement, however, the anode is provided with a flange 21, capacity coupled to the flange 21' through the insulating collar 30, preferably of mica. The output cavity resonator comprises the cylindrical member 31 closed at its bottom by means of the plate 32. Thus there is provided a cavity resonator formed by elements 21, 31 and 32. The anode is insulated for direct voltages and currents. The grid flange 27 is clamped in a manner similar to that in Figure 1.

The input cavity resonator in the arrangement shown in Figure 2 includes the collar 33 between which and the cathode pins 18 is mounted a modified form of short circuiting condenser including outer ring 34 and inner ring 35 insulatively separated by means of the mica collar 36. Adjusting means for the short circuiting condenser includes the extensions 37 and 37' on outer ring 34. The extensions are threaded to receive adjusting screws 38 and 39 rotatably supported by the plate 32 which is recessed to

receive the enlarged ends 40 and 41 for rotation. Rotation of screws 38 and 39 cause the condenser to move away from or towards the base of the tube shown in Figure 2. The output may be taken by a conventional coupling loop not shown.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having an anode, a grid and a cathode, said grid having a radially directed flat conducting member connected therewith, said cathode having terminals extending normal to the plane of and through said conducting member, a collar having one end connected to said conducting member and surrounding said terminals and coaxial with said terminals, and a first means including an inner and outer conducting ring having resilient fingers thereon contacting said terminals and said collar, said rings being secured together insulatingly from each other by means of an insulating collar, said terminals, collar and means providing a resonator, and a second means for adjusting said first means longitudinally of said collar and terminals and including a screw means supported adjacent said collar, and means extending between said rings and said screw means whereby said first means may be adjusted longitudinally.

2. An electron discharge device having an anode, a grid and a cathode, said grid being provided with a flange transverse to the longitudinal axis of said electron discharge, cathode terminal pins extending through and normal to the plane of the grid flange and positioned within a circle, and a cavity resonator coupled between said anode and grid, and a second cavity resonator coupled between said grid and said pins and including a collar supported by the flange and a tuning condenser mounted on said pins for longitudinal movement and contacting said pins

and the inside of said collar, and including a pair of coaxial conducting rings mounted in insulated spaced relationship, said collar having oppositely disposed slots extending from one end normal to said flange, means secured to said condenser and including a pair of oppositely disposed arms extending through said slots parallel to said flange and means including screw means rotatably secured to said flange and extending through said arms for adjusting said condenser to tune said second cavity resonator.

3. An electron discharge device having an anode, a grid and a cathode, said grid being provided with a flange transverse to the longitudinal axis of said electron discharge, cathode terminal pins extending through the envelope of the tube and normal to the plane of the grid flange and positioned within a circle, and cavity resonator coupled between said anode and grid, and a second cavity resonator coupled between said grid and said pins and including a collar supported by the flange and a tuning condenser mounted on said pins for longitudinal movement, and including a pair of coaxial conducting rings having resilient fingers contacting said pins and the inside of said collar, and means insulatingly supporting said collars in spaced relationship, said collar having oppositely disposed slots extending from one end normal to said flange, means secured to said condenser and including a pair of oppositely disposed arms extending through said slots parallel to said flange and means including screw means rotatably secured to said flange and extending thru said arms for adjusting said condenser to tune said second cavity resonator.
